DESIGN FOR A HAT

Harold H. Stahl, New York, N. Y.

Application April 30, 1947, Serial No. 138,695

Term of patent 3½ years

(Cl. D3—13)

To all whom it may concern:

Be it known that I, Harold H. Stahl, a citizen of the United States, residing in New York city, in the county of New York and State of New York, have invented a new, original, and ornamental Design for a Hat, of which the following is a specification, reference being had to the accompanying drawing, forming part thereof.

Fig. 1 is a side view of a hat showing my design,

Fig. 2 is the opposite side thereof,

Fig. 3 is a front view of the hat illustrating the hat in worn position, and

Fig. 4 illustrates the side view thereof in worn position.

I claim:
The ornamental design for a hat, substantially as shown.

HAROLD H. STAHL.
